UNITED STATES PATENT OFFICE.

WILLIAM E. BARTON, OF EAST HAMPTON, CONNECTICUT.

DESIGN FOR A SLEIGH-BELL.

SPECIFICATION forming part of Design No. 14,236, dated August 28, 1883.

Application filed July 16, 1883. Term of patent 14 years.

To all whom it may concern:

Be it known that I, WILLIAM E. BARTON, of East Hampton, in the county of Middlesex and State of Connecticut, have invented a new 5 Design for a Sleigh-Bell; and I do hereby declare the following, when taken in connection with accompanying drawing and the letters of reference marked thereon, to be a full, clear, and exact description of the same, and which 10 said drawing constitutes part of this specification, and represents a side view.

This invention relates to a design for that class of sleigh-bells which are of a spherical character, provided with a loose ball within 15 them; and the design consists in the configuration of the bell, as shown in the accompanying illustration and hereinafter described.

The special part of the bell embraced in my design is that from the edge of the annular 20 bead downward.

A represents the projecting bead. From above this line the bell is contracted to a central bearing-point, b, in any desirable lines or

curves. The under side of the bead is inclined 25 downward and inward to meet the lower part of the bell. This lower part is composed of a section, c, of inverted frustum of cone shape, and from the lower edge of this section the surface is rapidly contracted to a central point, d, as shown in the accompanying illustration. 30

The essential feature of my design is the inverted frustum of cone section intersecting the projecting bead above, and terminating below by a quick contraction to a central point, d.

I claim—

The herein-described design for sleigh-bells, consisting in the annular projecting bead A, the lower adjoining section, c, of inverted frustum of cone shape, which from its lower end rapidly contracts to a central point, d, 40 substantially as described, and shown in the accompanying illustration.

WILLIAM E. BARTON.
